corporation of New York

Application August 8, 1941, Serial No. 102,735

Term of patent 3½ years

To all whom it may concern:

Be it known that I, Gene Verrecchio, a citizen of the United States of America, residing in Providence, county of Providence, and State of Rhode Island, have invented a new, original, and ornamental Design for a Bracelet, of which the following is a specification, reference being had to the accompanying drawing, forming part thereof.

Fig. 1 is a plan view of a bracelet showing my new design.

Fig. 2 is an edge view thereof.

I claim:

The ornamental design for a bracelet, substantially as shown.

GENE VERRECCHIO.
